UNITED STATES PATENT OFFICE.

PETER KRUSE, OF BROOKLYN, NEW YORK, ASSIGNOR TO E. W. BLISS COMPANY, OF BROOKLYN, NEW YORK, A CORPORATION OF WEST VIRGINIA.

SHEET-METAL-WORKING MACHINE.

1,244,056.

Specification of Letters Patent. Patented Oct. 23, 1917.

Original application filed October 8, 1915, Serial No. 54,757. Divided and this application filed April 5, 1916. Serial No. 89,047.

To all whom it may concern:

Be it known that I, PETER KRUSE, a citizen of the United States of America, residing in the borough of Brooklyn, county of 5 Kings, city and State of New York, have invented certain new and useful Improvements in Sheet-Metal-Working Machines, of which the following is a specification.

This invention relates to sheet metal working machines and aims to provide certain 10 improvements therein.

Improved means for positioning and feeding sheets of metal from one position to another through the machine, are provided 15 by the present invention.

Other features of improvement will be hereinafter referred to.

The present application is a division of 20 my application Serial Number 54,757, filed October 8, 1915.

An embodiment of the invention is shown in the accompanying drawings.

The invention has been shown as incorporated in a machine for making can bodies.

25 The invention may, however, be otherwise embodied and otherwise applied.

In said drawings,—

Figure 1 is a side elevation of so much of 30 a body-making machine as is necessary to illustrate the invention;

Figs. 2 and 3 are respectively a vertical 35 sectional view, and a top plan view, illustrating in detail an embodiment of the improved feeding means.

In said drawings, the letter A designates a suitable table or bench forming the frame 40 of the machine, the general construction of the machine being similar to that described in my United States Patent No. 1,081,050, dated December 9, 1913. B is a feed bar working in a suitable guide-way in the top face of the table A (there being usually a plurality of such feed bars), the feed bar being preferably attached to a slide block

45 or piece C, and adapted to be reciprocated by a suitable means, as for instance, a train of links and levers b^1 , b^2 , b^3 connected to a crank pin b^4 upon a disk b^5 mounted upon a main drive-shaft D. The feed bar or bars

50 B are provided with feed fingers E. The arms E are pivoted upon the feed bars B, as at e^1 , and are adapted to be depressed against the pressure of a spring e^2 as they move rearwardly, being so depressed

by the sheets of metal with which they come 55 in contact in moving rearwardly. A stop e^3 limits the extent of the projection of the feed finger E above the upper face of the feed bars.

F^1 , F^2 , F^3 designate a plurality of mechanisms 60 by which the sheets of metal are worked upon. In the construction illustrated, the mechanism F^1 is a notching mechanism for forming notches in the sides of the sheets of metal, the mechanism F^2 65 is a flanging mechanism by which flanges or hooks are formed on the notched sides of the sheets, and F^3 is a body forming mechanism comprising a horn G around which the sheets are bent and the ends interlocked and joined in well-known manner. The function of the feed mechanism is to 70 feed the sheets of metal to an exact position with relation to these several mechanisms F^1 , F^2 , and F^3 , it being essential to 75 the formation of a can that the sheets be operated upon at precise points by the several mechanisms, and that the ends of the sheets and the notches therein shall properly match when wrapped around the horn and 80 the ends joined.

Sheets of metal are fed to the machine in any suitable manner (by hand if desired), and are carried forward by the feed fingers upon successive reciprocation of the feed bars B. An automatic feed I is shown, the construction of which is fully described in 85 Patent No. 1,081,050 aforesaid. As the feed bars B move forward, the sheets of metal X are carried forward by the feed fingers 90 beyond stops H^1 , H^2 and H^3 mounted upon a fixed part of the machine. The sheets of metal are preferably moved slightly beyond the stops, and, during the rearward movement of the feed fingers are moved rearwardly against the stops H^1 , H^2 or H^3 by 95 suitable means, as by the means P illustrated herein.

As shown, the means P may comprise a bar or blade p having a cam face p^1 thereon. The bar p is adapted to move or reciprocate vertically, and to this end it may conveniently be mounted upon a reciprocating part 100 of the notching mechanism F^1 (or the moving part of another mechanism), as illustrated at p^2 . The means P act to push the sheet rearwardly against the stops H^1 . Strips b^7 are preferably provided, which 105

are adapted to bear upon the upper sides of the sheets X with slight friction, the friction, however, not being sufficient to prevent the feeding or positioning movements of the 5 sheets.

The operation of the device is as follows:—The sheets of metal are engaged by the feed fingers E, and are carried forward beyond, and preferably slightly beyond, the 10 stops H¹, H² or H³. The sheets are then acted upon by the means P and pushed rearwardly against the stops. When in position with reference to the mechanisms F¹, F² and F³, the sheets are suitably acted upon 15 by said mechanisms.

The inventive ideas are capable of receiving other embodiments than those specifically illustrated and described.

What is claimed is:—

20 1. In sheet metal working machines, the combination of a feed means adapted to normally advance a sheet of metal beyond a predetermined position, means adapted to operate against the advance peripheral 25 edge of the sheet to position said sheet by moving it rearwardly, and means for moving said positioning means transversely of and out of the path of said sheet to permit the feeding of said sheet forwardly to an 30 other working position.

2. In sheet metal working machines, the combination of a feed means adapted to normally advance a sheet of metal beyond a predetermined position, a stop, means 35 adapted to operate against the advance peripheral edge of the sheet to position said sheet by moving it rearwardly against said

stop, and means for moving said positioning means transversely of and out of the path of said sheet to permit the feeding of 40 said sheet forwardly to another working position.

3. In sheet metal working machines, the combination of a feed means adapted to normally advance a sheet of metal beyond 45 a predetermined position, a stop for preventing back movement of the sheet, and a reciprocating finger, having an inclined edge, moving crosswise of, and adapted to operate against, the advance edge of the 50 sheet for setting the sheet back against said stop.

4. In sheet metal working machines, the combination of a reciprocating part for working on the sheet, a feed means adapted 55 to normally advance a sheet of metal beyond its true position with respect to said reciprocating working part, and a set-back finger carried by said reciprocating part, adapted to operate against the advance peripheral edge of the sheet to accurately position said sheet by moving it rearwardly, said reciprocating part carrying said set-back means out of the path of said sheet to permit the feeding of said sheet forwardly 60 to another position beyond said working mechanism.

In witness whereof, I have hereunto signed my name in the presence of two subscribing witnesses.

PETER KRUSE.
